DESIGN FOR A CHAIR-ARM TRAY

Melvin Higgs, Pomona, and James W. Crall,
Los Angeles, Calif.

Application March 4, 1947, Serial No. 137,322

Term of patent 7 years

(Cl. D44—10)

To all whom it may concern:

Be it known that we, Melvin Higgs and James W. Crall, citizens of the United States and, respectively, residents of Pomona and Los Angeles, both in Los Angeles County, State of California, have invented a new, original, and ornamental Design for a Chair-Arm Tray, of which the following is a specification, reference being had to the accompanying drawing and forming a part thereof.

Fig. 1 is a plan view of a chair-arm tray showing our new design;

Fig. 2 is a longitudinal elevational view, and

Fig. 3 is a combined and elevational and sectional view thereof.

We claim:

The ornamental design for a chair-arm tray, substantially as shown.

MELVIN HIGGS.
JAMES W. CRALL.
